US0D1063841S

(12) **United States Design Patent** (10) **Patent No.:** **US D1,063,841 S**
(45) **Date of Patent:** **** Feb. 25, 2025**

(54) **ENERGY STORAGE DEVICE**

(71) Applicants: **HICONICS ECO-ENERGY DRIVE TECHNOLOGY CO., LTD.**, Beijing (CN); **HICONICS ECO-ENERGY TECHNOLOGY CO., LTD.**, Beijing (CN)

(72) Inventors: **Zhiyu Bi**, Beijing (CN); **Shaogeng Zhang**, Beijing (CN); **Lifen Lin**, Beijing (CN); **Ningshan Wu**, Beijing (CN); **Zhe Zhang**, Beijing (CN); **Neil Seungmyung Vincenti**, Beijing (CN); **Yu Ning**, Beijing (CN); **Junfeng Hou**, Beijing (CN)

(73) Assignees: **HICONICS ECO-ENERGY DRIVE TECHNOLOGY CO., LTD.**, Beijing (CN); **HICONICS ECO-ENERGY TECHNOLOGY CO., LTD.**, Beijing (CN)

(**) Term: **15 Years**

(21) Appl. No.: **35/518,275**

(22) Filed: **Aug. 14, 2023**

(80) **Hague Agreement Data**

Int. Filing Date: **Aug. 14, 2023**

Int. Reg. No.: **DM/231100**

Int. Reg. Date: **Aug. 14, 2023**

Int. Reg. Pub. Date: **Sep. 8, 2023**

(30) **Foreign Application Priority Data**

Jun. 26, 2023 (CN) 202330393978.9

(51) **LOC (15) Cl.** **13-02**

(52) **U.S. Cl.**

USPC **D13/110**

(58) **Field of Classification Search**

USPC D13/102, 103, 104, 106, 107, 108, 109, D13/110, 112, 118, 119, 184, 199

(57) **CLAIM**

The ornamental design for an energy storage device, as shown and described.

DESCRIPTION

The patent or application file contains at least one drawing executed in color. Copies of this patent or patent application publication with color drawing(s) will be provided by the Office upon request and payment of the necessary fee.

1. Energy storage device

1.1 : Perspective

1.2 : Front

1.3 : Back

1.4 : Left

1.5 : Right

1.6 : Top

1.7 : Bottom

The broken lines in the reproductions depict portions of the energy storage device that form no part of the claimed design.

1 Claim, 7 Drawing Sheets
(7 of 7 Drawing Sheet(s) Filed in Color)
